HERBERT L. JOHNSON AND JAMES H. GRANT, OF DEXTER, MAINE

CAM LOCK FOR SCREENS AND STORM WINDOWS

Application filed May 16, 1929. Serial No. 363,595.

The object of the invention is to provide a device for use in connection with screens and storm windows whereby, when the latter are positioned in place, they may be locked firmly against the frame to securely hold them in place and, in the case of storm windows, to hold the same so that all cracks between the window and frame are closed; to provide a device which is of simple construction and therefore susceptible of cheap manufacture and low marketing cost.

With this object in view, the invention consists in a construction and combination of parts of which a preferred embodiment is illustrated in the accompanying drawings, wherein:

Figure 1 is a front elevational view showing the invention applied as a means for holding storm windows.

Figure 2 is an edge elevational view of the structure of Figure 1.

Figure 3 is a perspective view of one of the brackets and its associated locking roller.

Figure 4 is a detail sectional view on the plane indicated by the line 4—4 of Figure 3.

While the invention is shown applied as a means for holding the storm sash 10, it is equally applicable as a means for holding a screen should that replace the storm sash on the window frame 11. The invention comprises a plurality of brackets having base plates 12 formed with integral arms 14, the latter being at right angles to the base plate, so that when the plate is attached to the frame 11, the arms will extend outwardly from the frame. The arm is reinforced with a web 15 formed integrally with it and the base plate.

Fasteners such as screws 16 are employed to secure the base plate to the frame 11, these screws passing through slots 17 formed in the base plate and opening on that edge of the base plate where the arm is positioned. The slots 17 provide for slight adjustment of the brackets in mounting, so as to most conveniently position them.

The arms act as side guides for the storm sash 10 and the locking means consist of rollers 18 of which each bracket is provided with one, the rollers being rotatably mounted on

pins 19 carried at the outer ends of the arms and disposed eccentrically of the rollers. Each roller is provided with a plurality of peripheral sockets 20 adjacent its mounting pin 19, the sockets being for the selective reception of a pin wrench by which the rollers may be rotated so as to swing them into clamping engagement with the sash, since they overhang the outer face of the latter.

Obviously the locking operation constitutes the turning of the rollers toward the sash when they are brought into binding engagement with the latter and force the sash against the frame 11 between which and the sash a dust strip 21 may be inserted which of course may be omitted where the invention is employed as a screen holding means. To release the sash, the rollers are swung away from the latter, when the sash may be dropped down between the brackets to displace them.

The invention having been described, what is claimed as new and useful is:

1. In combination with a window frame and covering element therefor, brackets mounted on the frame on opposite sides of the latter and embodying projecting arms acting as side guides for the covering element, and clamping members carried at the extremity of the arms and in bearing engagement with the outer face of the covering element.

2. In combination with a window frame and covering element therefor, brackets mounted on the frame on opposite sides of the latter and embodying projecting arms acting as side guides for the covering element, and clamping members carried at the extremity of the arms and in bearing engagement with the outer face of the covering element, said clamping members consisting of rolls having pivotal mountings on the arms disposed eccentrically of the rolls.

3. In combination with a window frame and covering element therefor, brackets mounted on the frame on opposite sides of the latter and embodying projecting arms acting as side guides for the covering element, and clamping members carried at the extremity of the arms and in bearing engage-

ment with the outer face of the covering element, said clamping members consisting of rolls having pivotal mountings on the arms disposed eccentrically of the rolls and the 5 rolls being formed on the periphery adjacent the pivots with spaced sockets for selective use with a pin wrench.

4. A storm sash and screen holding element consisting of a bracket having a base 10 plate provided with an arm extending therefrom, and a roll having an eccentric pivotal mounting at the extremity of the arm and provided with peripheral sockets for the reception of a pin wrench, the base plate having 15 fastener receiving slots opening at that edge of the plate at which the arm is disposed.

In testimony whereof they affix their signatures.

HERBERT L. JOHNSON.
JAMES H. GRANT.
